UNITED STATES PATENT OFFICE

THOMAS M. MATTHEWS, OF TALLAHASSEE, FLORIDA, ASSIGNOR TO MATTHEWS AUTOMATIC TRAFFIC CONTROL CO., OF TALLAHASSEE, FLORIDA, A CORPORATION OF FLORIDA

TRAFFIC SIGNAL FOR HIGHWAYS

Application filed April 26, 1928. Serial No. 273,010.

The invention relates to means for signaling traffic on highways and particularly to means for stopping or slowing of vehicular traffic at intersecting roads or cross roads, 5 and railroad crossings, and has for its object the provision of a traffic signal that is operated by the approaching vehicle and comprising pivoted platforms mounted over a pit in the highway that are arranged for 10 simultaneous actuation by means of arms secured to the platforms and pivotally connected together, the adjacent free ends of the platforms being spaced and providing a plate arranged between the free ends of the 15 platforms for pivotal movement and connected for movement with the platforms, the plate when the platforms are in a depressed position forming a bridge connecting the platforms, and when in a non-bridging position inclined upwardly above the platform 20 and serving as a signal. The plate is provided with a weighted arm that normally holds it in raised position, moving to such position when the platforms are relieved of 25 the weight of the vehicle, the connection between the plate and the platforms also returning the platforms to a normally upwardly and inwardly inclined position.

The invention will be described in detail 30 hereinafter and will be found illustrated in the accompanying drawings in which

Figure 1 is a central longitudinal sectional view of the improved traffic signal showing it in signaling position.

Figure 2 is a top plan view showing the platforms and bridging plate in lowered positions,

Figure 3 is a transverse sectional view on a plane indicated by the line 3—3 of Figure 1,

Figure 4 is a fragmental detail view of the signal means on the bridging plate, and

Figure 5 is a sectional view on a plane indicated by the line 5—5 of Figure 1.

In the drawings similar reference characters are used to designate corresponding parts in all the views.

The traffic signal is designed to be installed in a vehicular highway such as indicated at A and over a pit B formed in the

highway, and has two oppositely arranged platforms 1 and 2 hinged as shown at 3 and 4 respectively at the opposite ends of the pit B. Secured to the under side of the platform 1 are arms 5 that are connected to the platform 1 by means of struts 6. Secured to the under side of the platform 2 are arms 7 that are connected to and support the platform 2 by means of struts 8. Arms 5 are extended beyond the free end 55 of the platform 1 and when the platforms 1 and 2 are in normal position as shown in full lines in Figure 1 the free ends of the arms 5 underlie the free ends of the arms 7. The free ends of arms 5 and 7 are connected by links 9.

Ten indicates a roller that is mounted in a race 11 in the upper side of each arm 5 adjacent to its free end that engages a recess 12 in the under side of mating arms 7 70 and serves as a bumper and bearing for said arms when engaged as shown in full lines in Figure 1. The roller 10 is held in position by means of a link 13. 14 indicates a plate that is hingedly mounted as shown at 75 15 intermediate of the free ends of the platforms 1 and 2 and is connected for operation with the platforms by means of links 16 pivotally engaging the under side of the plate 14 as shown at 17 and pivotally connected with the arms 5 as shown at 18. Secured to the plate 14 is an arm 19 to which is secured the weight 20 and that normally tends to hold the plate 14 and the platforms 1 and 2 in the position shown in Figure 1 80 85 in full lines. When either of the platforms 1 or 2 is depressed by the weight of a vehicle, the platforms will be lowered into the position shown in broken lines in Figure 1 and simultaneously therewith the plate 14 90 will be moved into the position shown to bridge the space between the free ends of the platforms so as to make a continuous roadway over a pit for the vehicle.

The upper face of the platform 14 is provided with a directional signal such for instance as "Slow" as shown at 21 and a plurality of bulls' eyes 22, said signals being made of reflecting material and colored suitably as a warning signal to indicate to 95 100

traffic that there is a dangerous crossing ahead and to proceed slowly, the apparatus being adapted to be so placed as to give the required signal to traffic for instance at 5 highway cross roads.

Secured to the rear or under side of the plate 14 is an inclined plate 23 on which is the directional signal "Stop" as indicated at 10 24 and a plurality of bulls' eyes 25, also made of reflecting material and suitably colored, it being apparent that where traffic is to be stopped, as for instance at a railroad crossing or at a side road to a thoroughfare, the apparatus will be so placed that the 15 traffic will be compelled to run on the platform 1 and brought to a standstill by the signals 24 and 25.

What is claimed is:—

1. In combination with a roadway having 20 a pit therein, platforms hingedly secured at opposite ends of the pit and having their adjacent ends spaced, arms secured to said platforms and having their adjacent ends overlapping, links connecting the overlapping ends of said arms, a plate pivotally mounted between the free ends of the platforms, means connecting said plate and arms to move the plate simultaneously with the platforms, the platforms being depressible 25 by the weight of vehicles thereon and the plate movable to bridge the space between the platforms when depressed, and a weighted arm on the plate normally holding it in non-bridging position and the platforms in upwardly inclined positions.

2. In combination with a roadway having 30 a pit therein, platforms pivotally supported at opposite ends of said pit and having their free ends spaced, said platforms being normally upwardly inclined toward each other 35 and adapted to be depressed by the weight of a vehicle on either platform, downwardly inclined arms on the platforms and having their ends overlapping, links connecting the overlapped ends of the arms, a plate pivotally mounted between the free ends of the arms, normally in an upwardly inclined position and movable with the platforms when depressed to bridge the space between the 40 platforms, links connecting the platform to the arms to actuate the plate simultaneously with the platforms, and a weighted arm on the plate and normally holding the plate and platforms in raised positions.

55 In testimony whereof I affix my signature.

THOMAS M. MATTHEWS.
